UNITED STATES PATENT OFFICE.

THEODORE HAVILAND, OF AMBAZAC, FRANCE.

DESIGN FOR A COVERED DISH.

SPECIFICATION forming part of Design No. 23,773, dated November 6, 1894.

Application filed October 12, 1894. Serial No. 525,727. Term of patent 7 years.

To all whom it may concern:

Be it known that I, THEODORE HAVILAND, a citizen of the United States, residing at Am-bazac, in the Department of Haute-Vienne and 5 Republic of France, have invented and pro-duced a new and original Design for Dishes; and I do hereby declare the following to be a full, clear, and exact description of the same, reference being had to the accompanying 10 drawings, forming a part thereof.

The principal feature of my design consists in a low covered dish having a regular series of two rays proceeding from the outer edge or base of the dish that lose themselves in the 15 body of the dish. The handles are made to represent oak-wood with leaves and acorns.

Figure 1 represents a side view of the dish, and Fig. 2 a face view of the cover.

In Fig. 1, A represents a series of two rays 20 which proceed from the base and edge of the

dish. Between the series of two rays A A at the base of the dish is ornamental scroll work.

The handles B B are made to represent a branch of oak wood ornamented with oak leaves and acorns. This peculiarity of the 25 handles is more clearly illustrated in Fig. 2 where a face view of the handles is given.

The series of rays in the cover are made to correspond with the series of rays in the body of the dish.

What I claim is—

The design for dishes substantially as herein shown and described.

In testimony whereof I affix my signature in presence of two witnesses.

THEODORE HAVILAND.
